CHARLES W. GIRVIN, OF PHILADELPHIA, PENNSYLVANIA.

ART OF ELECTRICAL PRECIPITATION OF PARTICLES FROM FLUID STREAMS.

1,378,224.

Specification of Letters Patent. Patented May 17, 1921.

Application filed February 16, 1918. Serial No. 217,489.

To all whom it may concern:

Be it known that I, CHARLES W. GIRVIN, a citizen of the United States, residing in the city and county of Philadelphia, State 5 of Pennsylvania, have invented new and useful Improvements in the Art of Electrical Precipitation of Particles from Fluid Streams, of which the following is a specification.

10 This invention relates to the art of electrical precipitation of particles from fluid streams.

Practice of this art involves the creation of an ionization field or fields in the flow 15 path of a stream and collection of the deposits on the stream boundary or boundaries. The present invention is designed as one embodiment in which the practice forming the basis of the patent granted to me 20 January 1, 1918, No. 1,252,104, may be conveniently carried out, the disclosure of said patent providing the use of a rotatable deposit-collecting electrode system, the ionization field or fields having permanently- 25 located inactive portions accessible to the deposit-laden boundaries, the deposits being removed while in such field portions. As a result the deposit-laden surfaces are automatically cleaned, enabling the apparatus to 30 operate continuously with little or no liability of the formation of dangerous disruptive discharge effects.

In the present embodiment various details of construction of an apparatus adapted for wide service conditions are presented, these details being designed to meet various minor problems which may arise in meeting varied conditions of service, these solutions having, through experiments, been found 40 to take care of the general conditions which may be anticipated.

For instance, the use of annular fields tends to complicate stream distribution resulting in decreased capacity for obvious 45 reasons. One feature, therefore, is the means whereby stream distribution to the fields is rendered more uniform.

Another feature is the approximate control of the stream flow path as to practically 50 eliminate movement of stream contents through the "inactive" portion of the field without being subjected to active field action.

Another feature is the substantial isolation of the inactive portion of the field to 55 practically eliminate the presence of strain lines at the point of deposit-removal, thereby providing a space through which deposits may freely fall. This space may also be utilized for the passage of counter-currents 60 which aid in causing lighter particles to be carried into the collection receptacle, a feature of advantage where the deposits may tend to float, as for instance deposits of 65 soot, etc.

To these and other ends, the nature of which will be readily understood as the invention is hereinafter disclosed, said invention consists in the improved construction and combination of parts hereinafter 70 fully described, illustrated in the accompanying drawings, and more particularly pointed out in the appended claims.

In the accompanying drawings, in which similar reference characters indicate similar 75 parts in each of the views,—

Figure 1 is a diagrammatic sectional view taken vertically through a precipitating apparatus according to the present embodiment.

Fig. 2 is a horizontal sectional view taken through the precipitating chamber.

Fig. 3 is a detail cross-sectional view taken through an active portion of a field.

Fig. 4 is a detail sectional view taken 85 through the inactive portion of the field.

10 designates the rotatable support, shown as carrying a plurality of concentrically-arranged circular walls 11, these walls providing the deposit-collecting surfaces, being 90 preferably grounded, although they may be connected to the opposite side of the source of electrical supply from that connected to the active electrode system. To permit of securing the walls in position, support 10 is 95 more or less spider-like (Fig. 2), the supporting division walls preferably being wedge-shaped, as at 10^a toward the direction of stream advance. Support 10 may also carry additional wedge-shaped rings 10^b, 100 these wedge shaped portions being preferably provided to more or less direct the stream contents as they enter the precipitating chamber.

In the present embodiment the active 105 electrode system is in the form of an upper

spider 12 which includes annular rings 12^a from which depend bars 13, the lower ends of the latter being secured in members 14 of more or less ring shape with a portion 5 of the ring omitted, the lower portion of the members also being preferably wedge-shaped in cross-section. Bars 13 preferably extend vertically—although they may vary therefrom under certain conditions—and 10 are of suitable cross-section, preferably angular with opposite edges facing the walls 11 when the electrode is in position.

As shown in Fig. 1, spider 12 is supported from a spider 15 by means of insulators 16, 15 spider 15 being adjustably mounted on brackets 17 carried by a casing 18 which surrounds the precipitation portion of the apparatus. The length of the bars 13 are such as to preferably locate members 14 20 above the bottom plane of walls 11, thus maintaining the distance factor of the active electrode system from the support of of the collecting system.

Spider 12 is connected to a suitable source 25 of electrical supply, such for instance as a high tension direct current generator, the collecting system being connected to ground or to the opposite side of the generator. It will be understood, of course, that the source 30 of electrical supply may be of any of the well-known types, the apparatus operating with current of the pulsating or continuous current, etc., types, as pointed out in the prior patent.

Support 10 is mounted rotatably on a stationary support 19 of proper configuration, rolls or other form of anti-friction means being preferably employed, support 10 being driven in suitable manner, as for instance by a roller rotated by a shaft 20 operatively connected to a source of power—shown as a motor 21—through suitable connections such, for instance, as a worm and worm-gear drive.

Casing 18 is carried by support 19 and encloses outer wall 11, the upper portion of the casing providing the entrance to the off-take for the cleaned fluid.

As will be understood, bars 13 coöperate 50 with the opposing surfaces of walls 11 to produce electric fields, the strain line effect being indicated somewhat in Fig. 3, being more or less individual to each bar. Therefore, by proper spacing of the bars the 55 strain lines from adjacent bars will closely approach or overlap with the result that a substantially continuous field throughout the sphere of influence of the bars, any apparently inactive portions between bars not 60 affecting the general operation owing to the wedge-shape of members 14, the latter tending to direct the entering stream away from the bars and therefore into the active field portions. The general arrangement therefore provides for a plurality of vertically ex-

tending strain-line zones positioned to more or less overlap or closely approach, the direction of length of the zones being in the direction of stream travel.

As heretofore referred to, the fields are 70 formed with active and inactive portions, the latter being provided by omitting a predetermined number of bars 13—as indicated in Fig. 2, for instance—the absence of such bars obviously leaving the space practically 75 free from strain lines and hence not adapted to the ionization action which takes place in the strain line portion. This portion of the field therefore becomes inactive for precipitating purposes and can be employed as the 80 point where cleaning of the collecting electrodes can take place, the deposit-removal devices being located in these portions.

As in the prior patented structure, cleaning is had by the use of stationary structures 85 which act to scrape or brush the deposit-laden walls, the present disclosure employing a plurality of brushes 22 carried by elements 23 having a general cross-sectional configuration such as shown in Fig. 4, thus 90 projecting a curved face in the direction of advancing deposits and in advance of the brushes, forming a pocket-like space in immediate advance of the brushes, the deposit-laden wall entering this space in reaching 95 the brushes.

Element 23 and brushes 22 are preferably metallic, and since the brushes are in contact with the collecting walls or the deposit thereon, any strain-line effect which might 100 tend to enter into the pocket portion of the field, is taken up or shunted by the metallic connection between the elements and the grounded walls through the brushes. Consequently, the pocket-like spaces will be free 105 from strain-line action and form passages within which the removed deposits will readily move downwardly into the dust hopper 24 located therebelow, these deposits being unaffected by the field action, these 110 elements thus practically shielding the deposits during the removal period. As presently pointed out, there is substantially no upwardly flowing fluid currents within these pocket-like spaces, and hence, under ordinary operating conditions, the deposits will drop by gravity.

Should the deposits be of a type which normally float, counter-currents can be set up in these spaces as by the delivery of suitable fluid streams—air or 115 cleaned gas—into the upper end of the pocket-like spaces, nozzles 40 being shown to indicate the direction of delivery. By the use of stream fluid which has been cleaned, the fluid introduced can reenter the general stream at the lower end of the spaces or through the side opening leading into the pocket.

In the present embodiment of the invention the direction of flow of the stream is 120

upward, the stream contents being introduced into a chamber below the precipitating portion of the apparatus and flowing upwardly into the latter with or without the aid of auxiliary means—such as pressure or suction—as may be found necessary. Since it is desirable, for operating purposes that the stream contents be distributed more or less uniformly throughout the active portions of the fields, thereby providing more uniform action and the ability to operate advantageously with maximum rates of stream flow, I prefer to employ a distribution element by means of which the stream is caused to be properly distributed and delivered into the precipitating structure under substantially uniform conditions as to rate of flow, distribution and pressure.

The general apparatus for producing these results, as disclosed, comprises a funnel-shaped casing 25 extending downward from support 19, this casing forming the upper end of a receiving chamber 26 for the stream contents, chamber 26 having a configuration which will cause the point of juncture of its walls with the lower end of casing 25 to act in the nature of a constricted neck 27 between the chamber and the interior of casing 25, chamber 26 operating somewhat as an expansion chamber for the stream contents entering through pipe 28 which forms the conduit for the stream contents. As shown, the space within casing 25—with the exception of that occupied by the dust or deposit hopper 24—is provided with a plurality of partitions 29 which sub-divide the space into cell-like passageways, open at opposite ends, the lower inlet ends having a smaller cross-sectional area than the upper outlet ends.

As will be understood, therefore, from Fig. 1, the stream contents are delivered into chamber 26 in which more or less equal pressure is had, and then pass upwardly toward and into the contracted neck 27 while under such equal pressure conditions, the contracted upper end of chamber 26 aiding in providing this result. Since partitions 29 extend into this neck, distribution is equalized and the flow through the gradually-increasing area of the cells provides for proper delivery of the contents at the lower end of the precipitating chamber. To aid this result, I preferably discharge the stream contents from pipe 28 in a downward direction—opposite the direction of flow in chamber 26—and thereby break down any tendency of the pressure of the entering stream contents disturbing the desired equal pressure conditions at the contracted neck. In addition, this arrangement permits the lower end of chamber 26 to be formed as a pocket into which heavier particles may gravitate, the pocket having a suitable closure, indicated conventionally

at 30, through which these deposits may be removed. Obviously, such particles may so gravitate at any point in the upward travel of the stream, and the contracted lower end of the chamber will cause them to pass into the pocket, thereby providing a preliminary treatment of the stream contents which will aid in the general operation.

Dust or deposit hopper or receptacle 24 is located below the inactive portions of the field, as heretofore pointed out, and may be of any desired shape. I prefer, however, to employ a configuration of its upper end such as will cause the hopper to serve in the nature of a baffle for the inactive field portions. I also prefer to incline the inner wall of the hopper in such way as to tend to deflect the stream contents without forming any material dead pocket of the stream to disturb the stream flow. The hopper is provided with any suitable form of closure—indicated conventionally at 24^a—for removal of the collected deposits.

As a guide in determining the comparative size of the upper end of the hopper when employed for baffle purposes, I would state that experiments have shown that under general conditions and in an apparatus of comparatively large capacity, I have found that this area need not exceed $.2(.7854D^2)$ where $.7854D^2$ equals the total cross-sectional area of the precipitation chambers, D representing the diameter of the outside precipitating wall, giving an approximate net cross-sectional area of the cleaner as $.63D^2$. As an example of general size of apparatus, the following may be considered:

An apparatus designed to treat 50,000 cubic feet of gas per minute, with the stream flow rate as 8 feet per second, would employ an apparatus having the total net effective cross-sectional area of 104 square feet, with the diameter 12.8 feet, these dimensions being approximate.

As will be understood from Fig. 2, any stream contents which would enter into the inactive portions of the field, must traverse active field portions and be subjected to the action thereof.

If desired, suitable packing may be employed to prevent leakage of gas stream contents from chamber 26 into the space external of outer wall 11.

While I have herein shown and described a preferred embodiment of the invention, it will be readily understood that changes and modifications therein may be found necessary or desirable in meeting the various exigencies of use, and I desire to be understood as reserving the right to make any and all such changes or modifications therein as may be found desirable or essential in so far as the same may fall within the

spirit and scope of the invention as expressed in the accompanying claims when construed broadly.

Having thus described my invention, 5 what I claim as new is:

1. In apparatus of the character described and wherein opposing electrode systems are movable relatively to each other and adapted to produce an electric field or 10 fields, means operative to isolate a space of predetermined cross-sectional area from field activity, and means whereby deposits collected on a face of one of said systems will be removed from such face while free 15 from such activity.
2. In apparatus of the character described and wherein opposing electrode systems are movable relatively to each other and adapted to produce an electric field or 20 fields, means for removing deposits from a deposit-collecting face of one of said systems, said means including an element operative to isolate a space of predetermined cross-sectional area free from field activity and within which deposit removal may 25 be had.

3. In apparatus of the character described and wherein opposing electrode systems are movable relatively to each other 30 and adapted to produce an electric field or fields, a rotatable wall forming part of one of the systems and having a deposit-collecting face, and means for removing the deposits from said face, said means including 35 an element operative to isolate a space of predetermined cross-sectional area free from field activity, said wall forming a space-defining wall.

4. Apparatus of the character of claim 40 3, characterized in that the element operative to produce the isolated space carries means for removing the deposits, said means being located at the rear of the space, whereby the deposits are free to travel in 45 such space.

5. In apparatus of the character described and wherein opposing electrode systems are 50 movable relatively to each other and adapted to produce an electric field or fields, an element within the field and operative to isolate a space of the field free from field activity, said space being adjacent a deposit-laden face of one system, and means operative on deposits of said face within 55 said space for removing such deposits from the deposit laden face.

6. Apparatus as in claim 5 characterized in that the means extends in the direction of stream travel through the apparatus.

- 60 7. Apparatus as in claim 5 characterized in that the means extends substantially vertically.

8. Apparatus as in claim 5 characterized in that the space has its direction of length

extending vertically, whereby the removed 65 deposits may gravitate from the space.

9. Apparatus as in claim 5 characterized in that the space has its direction of length corresponding to the direction of flow of the stream being treated.

10. Apparatus as in claim 5 having means 70 for directing a fluid pressure in the direction of length of the space.

11. Apparatus as in claim 10 characterized in that the direction of fluid pressure 75 flow is counter to the direction of stream flow through the apparatus.

12. In apparatus of the character described, wherein opposing electrode systems are adapted to produce an electric field operative 80 for precipitating purposes and wherein the flow path of the stream is confined within substantially concentric limits, a chamber in advance of the field for receiving the stream contents to be treated, 85 said chamber having a contracted outlet and tending to control the stream distribution, and means intermediate said outlet and the field for substantially maintaining the stream distribution during its passage to 90 and within the zone of precipitation activity.

13. Apparatus as in claim 12 having means operative within the chamber for eliminating stream particles therefrom by 95 gravitation.

14. In apparatus of the character described, wherein opposing electrode systems are adapted to produce an electric field operative 100 for precipitation purposes and wherein the flow path of the stream is confined within substantially concentric limits, a chamber in advance of the field for receiving the stream contents to be treated, 105 said chamber having a contracted outlet and tending to control the stream distribution, and a cellular structure intermediate said outlet and the field for substantially maintaining the stream distribution during its passage to and within the zone of precipitation 110 activity.

15. In apparatus of the character described, wherein opposing electrode systems are movable relatively to each other and adapted to produce an electric field operative 115 for precipitation purposes, and wherein precipitated deposits are removed from a deposit-laden face at a predetermined point of such field, means for introducing a stream to such field, and a deposit-receiving 120 chamber located in the stream flow-path and operative as a direction-control factor in the stream movement to the field.

16. In apparatus of the character described, wherein opposing electrode systems 125 are movable relatively to each other and adapted to produce an electric field operative for precipitation purposes, and where-

in precipitated deposits are removed from a deposit-laden face at a predetermined point of such field, means for introducing a stream to such field for treatment, and 5 means in the flow path of the stream for controlling the direction of stream movement to individual portions of the field.

17. Apparatus as in claim 16 characterized in that the means includes a distributing element operative to substantially equalize stream distribution to the field.

18. Apparatus as in claim 16 characterized in that the means includes an instrumentality operative to limit stream delivery 10 to active portions of the field, and a distribution element operative to substantially equalize the distribution of the delivered stream.

19. In apparatus of the character described, wherein opposing electrode systems are movable relatively to each other and adapted to produce an electric field having active and inactive portions operative for precipitation purposes, and wherein precipitated deposits are removed from a deposit-laden face at a predetermined point in the inactive portion of the field, means for introducing a stream to such field for treatment, and means operative in the 25 stream flow path in advance of the field

for controlling the direction of stream movement to individual portions of the field and active to limit stream delivery to active portions of the field.

20. In apparatus of the character described, wherein opposing electrode systems are movable relatively to each other and adapted to produce an electric field having active and inactive portions operative for precipitation purposes, and wherein precipitated deposits are removed from a deposit-laden face at a predetermined point in the inactive portion of the field, and a deposit-receiving chamber located in the stream flow path beneath a field inactive portion and 40 operative to limit stream delivery to active portions of the field.

21. In electrical precipitating apparatus, opposing electrode systems adapted to produce an electric field, the deposit-collecting system including concentrically-arranged spaced-apart faces, the active discharge system including a plurality of spaced-apart bars extending in parallelism and arranged in a segmental series positioned substantially concentric with the outer face of the collecting system and between adjacent collecting faces of such system.

Signed this 13th day of February, 1918.
CHARLES W. GIRVIN.
